FIG. 8.

UNITED STATES PATENT OFFICE.

WALTER G. TRAUTMAN, OF CLEVELAND HEIGHTS, OHIO, ASSIGNOR TO THE CLEVELAND FOLDING MACHINE CO., OF CLEVELAND, OHIO, A CORPORATION OF OHIO.

PAPER-FOLDING MACHINE.

Application filed May 16, 1924. Serial No. 713,719.

To all whom it may concern:

Be it known that I, WALTER G. TRAUTMAN, a citizen of the United States of America, residing at Cleveland Heights, in the county 5 of Cuyahoga and State of Ohio, have invented certain new and useful Improvements in Paper-Folding Machines, of which the following is a specification.

My invention relates to improvements in 10 paper-folding machines and has for its object the equipment and mounting of the folding plates of such machines whereby they may be more readily adjusted to suit the varying requirements of the folding machine and may be handled without removal 15 from the support or frame. I preferably associate therewith a fixed transverse feed.

Hitherto it has been necessary bodily to remove or insert the plates associated with 20 the folding rolls of a paper-folding machine; substituting such folding plates, when required by deflectors positioned before the requisite set or sets of folding rolls. This necessarily entails considerable labor and 25 time for adjusting the paper-folding machine to accomplish the different folding operations required by different jobs.

Accordingly, I have improved this class 30 of paper-folding machine by mounting the folding plates slidably within the frame for easy adjustment toward and from the coacting rolls. Moreover, the folding plates preferably are equipped with individual deflector members adapted to be actuated into 35 and out of operative relation with respect to said folding plates and rolls. Thus my improvements render it unnecessary to remove either the folding plates or the deflectors from the machine, since they are capable 40 of every adjustment required thereof merely by sliding the folding plates into or out of operative relation with the corresponding rolls and adjusting the associated deflectors respectively in their inoperative 45 or operative positions, as required.

The features of my improvement may be made clear and the utility may be fully explained by making reference to the accompanying drawings, wherein:

Figure 1 is a plan view, partially broken away, illustrating a paper-folding machine equipped with my improvements.

Fig. 2 is a longitudinal sectional view thereof,

Fig. 3 is an enlarged fragmentary section 55 on line 3—3, Fig. 2,

Fig. 4 is an enlarged transverse section centrally broken away on line 4—4, Fig. 2,

Fig. 5 is another enlarged fragmentary section illustrating the adjustable deflector, 60

Fig. 6 is an enlarged fragmentary section and plan on line 6—6, Fig. 7, showing the folding rolls and deflectors in association with the folding rolls,

Fig. 7 is a fragmentary vertical section on 65 line 7—7, Fig. 6, and Fig. 8 shows a modification in longitudinal section.

Throughout the several figures of the drawings I have employed the same character of reference to indicate similar parts. 70

Attention may initially be directed to the somewhat diagrammatic showing of Fig. 2 wherein the frame *a* supports the feed table *b* adapted to convey the sheets between the feeding rolls *b'*, *b''* to the series of folding 75 and buckling rolls *c*, *d*, *e*, *f*, *g* and *h*. The folding plates *i*, *j*, *k* and *l* are operatively associated with said series of rolls and are slidably mounted within the frame, two by two, on either side of said series of rolls. 80

Each of said folding plates is provided with a pivoted deflector member *i'*, *j'*, *k'* and *l'* of suitable shape adapted individually to be adjusted in advance of the throats of their respective openings for the signatures, 85 whereby the particular folding plate may be rendered temporarily inoperative, merely by withdrawing said folding plates and securing them in their rearward positions of adjustment within their slides. As shown in 90 the drawings, only the second folding plate *j* of the series is left operative to permit the formation of a fold therein, while the deflector members serve otherwise to direct the signature through the rolls as a continuous 95 pass without operating thereon. As indicated, more particularly in Fig. 7, the folding and buckling rolls are pivotally mounted at their ends upon bracket members and

are spring pressed to secure their resilient 100 engagement in accordance with the well-known manner. Moreover, the deflectors are seen to be of slightly varying shapes in order to conform to the direction initially assumed by the signature in passing between 105 the respective pairs of rolls.

From the foregoing it will be understood that any folds may be provided for or omit-

ted from the operation of the folding apparatus, so that it is desirable to provide a fixed transverse feed or conveyor table, as best shown diagrammatically in Fig. 8.

5 Thus, in the modification shown, and with the adjustment rendering inoperative all but the second folding plate, the signatures will pass successively through the rolls with but a single folding operation and thence 10 between the feeding rolls $m\ m'$ and $n\ n'$ to the roller-bed σ of the transverse conveyor. These rolls σ , it may be assumed, will feed the signatures toward the opposite side of the folding machine and the importance of 15 having this transverse feed in a fixed or predetermined position is emphasized in the modern folding machine which commonly requires additional auxiliary mechanism to accomplish additional transverse folds or 20 other operations as more fully explained in my co-pending application Ser. No. 713,718. These features, however, form no part of my present invention which relates more particularly to the adjustment of the folding 25 plates and their deflector members in association with the fixed transverse feed per se.

Having now described the preferred embodiment of my invention and the operation thereof, I claim as new and desire to secure by Letters Patent, together with such modifications as may be made by those ordinarily skilled in the art, the following:

1. In a paper-folding machine, the combination with its frame provided with lateral supports of a plurality of folding plates slidably mounted respectively upon said supports, and deflector members adjustably positioned forwardly of said folding plates 35 and adapted to be actuated into and out of operative position, substantially as set forth.

2. In a paper-folding machine, the combination with its frame provided with lateral supports of a plurality of folding plates 45 slidably mounted respectively upon said supports, and deflector members pivoted each to each upon the forward portions of said folding plates whereby they are adapted to be actuated independently into positions in 50 advance of the respective folding plates or into inoperative positions for said deflectors, substantially as set forth.

3. In a paper-folding machine, the combination with its frame provided with lateral 55 supports of a plurality of folding plates

slidably mounted respectively upon said supports, folding and buckling rolls associated with said folding plates and means for individually securing the folding plates in forward and rearward positions of adjustment 60 with respect to the folding and buckling rolls, substantially as set forth.

4. The combination with a set of folding and buckling rolls in a paper-folding machine, of a folding plate associated therewith, means for adjusting it toward and from said rolls and a deflector member adjustably positioned upon the forward portion of said folding plate adapted to be actuated between said folding plate and rolls 70 when the former is rearwardly positioned, substantially as set forth.

5. The combination with a set of folding and buckling rolls in a paper-folding machine, of a folding plate operatively associated therewith, a slide supporting said folding plate before and adjacent to the rolls and permitting its adjustment with respect thereto, and adjustable means provided upon said folding plate for temporarily 80 blocking the entrance of the signature to the throat thereof, substantially as set forth.

6. In a paper-folding machine, the combination with a plurality of folding plates, of their associated folding and buckling rolls, 85 adjustable means provided upon each of said folding plates for temporarily blocking the entrance of the signatures thereto, and a fixed transverse conveyor stationarily mounted within the folding machine below 90 the lowermost set of rolls, whereby signatures of any desired number of folds may be fed laterally of the machine in predetermined position, substantially as set forth.

7. In a paper-folding machine, the combination with its frame provided with lateral supports of a plurality of folding plates slidably mounted respectively upon said supports, folding and buckling rolls operatively associated with said folding plates, deflector 100 means provided upon each of said folding plates adapted respectively to be interposed between them and the rolls, and a transverse feeding conveyor fixedly positioned within the frame beyond the lowermost rolls and 105 adapted to receive the folded signatures therefrom, substantially as set forth.

In testimony whereof I do now affix my signature.

WALTER G. TRAUTMAN.
